UNITED STATES PATENT OFFICE.

ARTEMUS N. HADLEY, OF INDIANAPOLIS, INDIANA.

HOISTING APPARATUS.

SPECIFICATION forming part of Letters Patent No. 768,746, dated August 30, 1904.

Original application filed April 15, 1898, Serial No. 677,727. Divided and this application filed August 8, 1902.
Serial No. 118,897. (No model.)*To all whom it may concern:*

Be it known that I, ARTEMUS N. HADLEY, a citizen of the United States, residing at Indianapolis, in the county of Marion and State of Indiana, have invented certain new and useful Improvements in Hoisting Apparatus, of which the following is a specification.

My invention relates to an improved hoisting apparatus, and the present application is a division of my application Serial No. 677,727, (Patent No. 687,229.)

The object of my invention is to provide horse-operated means for operating a hoisting mechanism.

The accompanying drawings illustrate my invention.

Figure 1 is a plan. Fig. 2 is a section on line 2 2 of Fig. 1. Fig. 3 is a detail. Fig. 4 is a longitudinal section just to the left of finger 20 in Fig. 1.

In the drawings, 4 indicates the tongue of a vehicle. Longitudinally movable upon tongue 4 is the usual doubletree 5, said doubletree being provided, however, with a bolt 6, the head 7 of which runs beneath the projecting flanges of a pair of angle-irons 8, mounted upon the tongue. Running back from the doubletree is a pair of converging chains 9, the adjacent ends of which are secured to a shoe 10. Shoe 10 is provided with a bolt 11, the head 12 of which runs beneath the flange of irons 8. Secured to shoe 10 is a cable 13, which runs to the hoisting-drum 14, provided with a return-spring. (Not shown.)

Drum 14 is fully described and claimed in the application above mentioned.

For the purpose of holding the doubletree against the pull of the horses I mount in suitable bearings 15 to rear of the normal position of shoe 10 a rock-shaft 16, provided with a finger 17, which lies normally immediately in front of said shoe. Shaft 16 is provided with a suitable operating-lever 18. In order to properly center shoe 10 and relieve bolt 11 from transverse stress, the front face of said shoe may be provided with a pair of ears 19, between which finger 17 may lie.

In order to prevent the forward movement of the harvester or other portable platform upon which the mechanism may be mounted when the load is being lifted, any suitable brake or lock may be used; but in order that its action shall be automatic I provide the locking-lever 20. Lever 20 is provided near its rear end with a notch 21, arranged to receive the projecting edge of the wheel-tire 22. Lever 20 is provided on its under side with a notch 23, arranged to receive a rib 24, carried by a base-plate 25. Base-plate 25 is provided with a pair of upwardly-extending ears 26, between which the locking-lever is mounted. In order to prevent the lever 20 from slipping in either direction, it is provided with lugs 27, arranged on each side of ears 26. The forward end of the locking-lever is passed over the rock-shaft and connected with an arm 28, carried by said shaft, the arrangement being such that when said shaft is rocked, so as to lift finger 17 away from shoe 10, the said locking-lever will be tilted until the edges of notch 23 grip the wheel-tire, the grip upon said tire being sufficient to maintain the several parts in their unnormal position until they are forced down by the operator.

In operation the operator throws lever 18 and its shaft 16 until finger 17 rises clear of shoe 10. The doubletree and shoe 10 may then be advanced along the tongue, thus operating the hoisting-drum 14. The rocking of shaft 16 swings lever 20 and causes the edges of notch 21 to grip the traction-wheel, and thus hold the vehicle. When the load has been lifted and dropped, the spring of drum 14 will draw shoe 10 and doubletree 5 back along tongue 4 to their normal positions, and finger 17 may then be thrown down in front of the shoe.

I claim as my invention—

1. In a hoisting apparatus, the combination with a suitable portable platform having a tongue, a horse-hitching means, such as a doubletree, mounted upon and movable along said tongue, a shoe connected with said hitching means and also provided with means to

which a cable may be secured, a rock-shaft mounted to the rear of the normal position of said shoe, and a finger carried by said shaft in position to be thrown in front of the normal position of the shoe.

2. In a hoisting apparatus, the combination with a suitable wheeled platform, of a horse-hitching means mounted thereon and provided with means to which a cable may be attached, means for releasing said hitching mechanism, and a brake or stop arranged to engage one of the wheels of said platform.

3. In a hoisting apparatus, the combination with a suitable wheeled platform, of horse-hitching means mounted thereon and provided with means to which hoisting mechanism may be connected, means for releasing said hitching means, a brake or stop arranged to engage one of the wheels of said platform, and intermediate connecting mechanism between said brake and releasing means whereby, when the

hitching means is released the brake will be thrown into engagement with the wheel.

4. In a hoisting apparatus, the combination with a suitable wheeled platform having a tongue, of a horse-hitching means mounted upon and movable along said tongue, a shoe connected to said means and adapted to be connected to a hoisting-cable, a rock-shaft, a finger carried by said rock-shaft in position to be thrown in front of the normal position of the shoe, a brake mounted in position to engage one of the wheels of the platform, and connections between the brake and rock-shaft for the purpose set forth. 35

In witness whereof I have hereunto set my hand and seal, at Indianapolis, Indiana, this 5th day of August, A. D. 1902.

ARTEMUS N. HADLEY. [L. s.]
